ATTORNEY

UNITED STATES PATENT OFFICE.

EDWARD B. NOWOSIELSKI, OF BLOOMFIELD, NEW JERSEY, ASSIGNOR TO SPLITDORF ELECTRICAL COMPANY, OF NEWARK, NEW JERSEY.

PUSH-BUTTON SWITCH.

Application filed April 18, 1923. Serial No. 632,965.

To all whom it may concern:

Be it known that I, EDWARD B. Nowosiel-
ski, a citizen of the United States, residing
at Bloomfield, in the county of Essex, State
5 of New Jersey, have invented certain new
and useful Improvements in Push-Button
Switches, of which the following is a de-
scription, reference being had to the accom-
panying drawing, and to the figures of refer-
10 ence marked thereon.

This invention relates to a switch of the
push button type and is particularly adapt-
ed for use in connection with the control of
the horn circuit used on an automotive ve-
15 hicle and as illustrated, the switch is adapt-
ed to fit in the upper end of the steering post
which carries the operating hand wheel.

It is the principal object of my invention
to provide a switch that is easy to operate
20 and one which will carry a considerable
amount of current without detriment to the
operating members.

While procuring the above results it is a
further object to provide a switch which is
25 relatively simple and cheap to manufacture.

In the drawing,

Figure 1 is a sectional view on an en-
larged scale through the switch.

Figure 2 is a bottom view of the body of
30 the switch shown in Fig. 1 with a section
broken away to show certain details.

In the drawing, 1 illustrates a casing hav-
ing an inturned flange 2 at one end. Fitting
within the casing 1 is an insulator 3 of any
35 suitable material. The insulator 3 has a cen-
tral bore, preferably of two diameters, in
the smaller of which a thimble 4 is somewhat
snugly positioned. Thimble 4 has a flange
5 adapted to fit within the larger part 6 of
40 the bore and when the flange 5 rests against
the shoulder formed by the bores of different
diameters, the end of the thimble projects
beyond the casing 1. The projecting end is
preferably threaded at 7 to receive a metal-
45 lic plate 8 moulded securely within a push
cap 9 of insulating material. The thimble
4 carries a spring 10, the outer end of which
rests against a metallic member 11, which
in turn is held against the outer end of the
50 insulator 3 by a disc type insulator 12.
From Fig. 2 it will be seen that the insulator
12 laps over the metallic member 11, which
is preferably formed somewhat like a clover
leaf, the arms resting in indentations in the

insulator 2, whereby the arms come substan-
tially flush with the end of insulator 3. The
parts of the end of the casing 1 may be bent
over as indicated at 13 to hold the insulator
12 and the member 11 in position. While
60 there are shown three clamps 13, it will be
understood that the entire rim of the casing
1 may be spun over to grip onto the insu-
lator 12. The insulator 3 has a second bore,
preferably of two diameters, in the smaller
65 of which is carried a plunger 14 which pro-
trudes beyond the end of the casing 1 into
contact with the plate 8. Plunger 14 is pro-
vided with a flange 15 which is positioned
in the bore of larger diameter and is nor-
70 mally held against the shoulder formed
by a bore of smaller diameter through the
medium of a spring 16, the outer end of
which engages one arm of the metallic mem-
ber 11. To the plunger 14 is attached an
75 electric conductor, preferably of strands of
small copper wire and this conductor or
cable 17 extends through the spring 16 and
passes through the hole 18 in the member 11,
where it is fastened thereto in any suitable
80 manner as by soldering.

The member 11 carries a screw 19 which
is used to connect the terminal wire to the
member 11. It is to be understood that the
casing 1 acts as one terminal of the circuit
and the member 11 and its screw contact 19
85 as the other, so that when the push cap 9
is operated, the greater portion of the cur-
rent is carried through the cable 17, plunger
14, plate 8 to the casing 1. The object,
therefore, of the cable 17 being to prevent
90 any detrimental amount of current passing
through the springs 10 and 16, which if al-
lowed to take place would change their ten-
sion and effect the operation of the switch.
The cable 17 and the plunger 14 are, there-
95 fore, relied on to carry the most of the cur-
rent through the switch.

The thimble 4 is made relatively long and
fits somewhat snugly within the bore pro-
vided for it in order that the push cap 9
100 will have no tilting effect when operated, but
rather will have a longitudinal movement,
the return of the button 9 being assured by
the combined action of the springs 10 and 16
together with the plunger 14.

It frequently happens that the caps of
push buttons of this character are broken,
and in order to easily renew one of the caps,

the screw arrangement as shown in Fig. 1 is preferred, whereby the cap may be removed without dismounting the switch.

5 A means of holding the switch in position in the steering column is indicated by screw 20 which is adapted to pass through into the steering column into engagement with a clamping plate 21 carried in a groove 22 in the insulator 3.

10 While I have indicated a preferred form of applying my invention in practice, I do not wish to be limited to the exact details shown and described, except as limited by the scope of the appended claims.

15 Having thus described my invention, what I claim is:

1. In a device of the class described, a casing, an insulator positioned within the casing and having two bores, a thimble enclosing a spring in one bore and a plunger and spring in the other bore, a cap carrying a metallic plate fastened to said thimble in such a manner that said plunger bears against said plate, a metallic member for engaging the ends of said springs away from said thimble and plunger with means for making an electrical contact therewith and means for holding said metallic member in position against the end of the insulator.

20 2. In a device of the class described, a casing, an insulator positioned within the casing and having two bores, one centrally located and the other spaced away from the central bore, a thimble enclosing a spring in the central bore, and protruding through the insulator, a plunger and spring in the other bore, said plunger protruding through the bore on the same end of the insulator as said thimble, a cap carrying a metallic plate

25 fastened to the protruding end of said thimble, whereby said metallic plate is brought into engagement with said plunger, a metallic member for engaging the ends of said springs which extend away from said thimble and plunger with means for making an electrical contact with said metallic member, and means including an insulator and the rim of the casing for holding said metallic member in position.

30 3. In a device of the class described, a casing having an inturned flange and an insulator positioned within the casing and against the flange, said insulator having a central bore of two diameters with a thimble

35 positioned in the smaller diameter and having a flange positioned in that part of the bore of larger diameter and adapted to engage that part of the bore of smaller diameter, a spring positioned within the thimble and causing it to protrude through the end of the insulator resting against the flange of the casing, a second bore of two diameters spaced apart from the first mentioned bore, a plunger positioned in that part of the sec-

40 ond bore of smaller diameter and having a flange positioned in that part of the second bore of larger diameter, a spring positioned in that part of the second bore having the larger diameter for causing the plunger to protrude through the same end of the insulator as said thimble, a cap carrying a metallic plate fastened to the protruding end of said thimble, whereby said plunger is brought into engagement with said plate, a metallic member for closing the opening of the bores of larger diameter and for applying tension to said spring, means for making electrical contact to said metallic member and means for holding said metallic member in position against the end of said insulator.

45 4. In a device of the class described, a casing, an insulator positioned within the casing and having a central bore, a thimble having a threaded end protruding through one end of the insulator with cooperating means between the insulator and thimble for limiting the amount of protrusion, a cap carrying a metal plate having a threaded hole to engage the threaded end of the thimble,

45 said insulator having a second bore with a plunger positioned therein and protruding through the same end of the insulator as said thimble with cooperating means between the insulator and plunger for limiting the amount of its protrusion, a spring positioned in said thimble, a spring in the second bore

50 engaging the head of said plunger, a metallic member for closing the ends of said bores and applying tension to said springs, means for fastening said metallic member in place and means for making an electrical connection thereto.

55 5. In an electric switch, a casing serving as one terminal of the switch, an insulator positioned within the casing, a thimble centrally carried by the insulator and having one end screw threaded and adapted to project through one end of the insulator, a push cap having a metallic plate for threading onto the threaded end of said thimble, a plunger carried by the insulator adjacent the thimble and having an end projecting through the insulator into engagement with

60 said metallic plate, a spring having one end positioned in the thimble, a second spring having one end against the plunger, a metallic member for engaging the opposite ends of said springs, means for holding the metallic member against the end of the insulator and means for making a wire connection to said metallic member.

65 6. In an electric switch, a casing serving as one terminal of the switch, an insulator positioned within the casing and having a wire terminal member fastened in position against one end of the insulator, means for completing a circuit from said terminal member to the casing including a thimble carried by the insulator and having an end

70 projecting beyond the insulator at the end

opposite to said terminal member, a push cap carrying a metal plate with means for engaging the projecting end of the thimble, said plate overlapping said casing and adapted to contact therewith, a spring carried by said thimble and having one end engaging said terminal member to normally keep the plate carried by the push cap out of contact with the end of said casing.

- 10 7. In an electric switch, a casing serving as one terminal of the switch, an insulator positioned within the casing and having a wire terminal member fastened in position against one end of the insulator, means for completing a circuit from said terminal member to the casing including; a thimble carried by the insulator and having a threaded end projecting beyond the insulator at the end opposite to said terminal member, a push cap carrying a metal plate having a threaded hole to engage the threaded end of the thimble, said plate overlapping said casing and adapted to contact therewith, a spring carried by said thimble and having one end engaging said terminal member to normally keep the plate carried by the push cap out of contact with the end of said casing, said thimble being so proportioned and fitted in the insulator that the push cap 30 cannot tilt when operated to close a circuit.

8. In an electric switch, a casing serving as one terminal of the switch, an insulator positioned within the casing and having a wire terminal member fastened in position against one end of the insulator, means for completing a circuit from said terminal member to the casing including; a thimble carried by the insulator and having an end projecting beyond the insulator at the end opposite to said terminal member, a push cap carrying a metal plate with means for engaging the projecting end of the thimble, said plate overlapping said casing and adapted to contact therewith, a spring carried by said thimble and having one end engaging said terminal member to normally keep the plate carried by the push cap out of contact with the end of said casing, and further means for assisting in keeping the push button plate away from the end of the casing and in completing said circuit consisting of; a plunger carried by the insulator and having one end projecting into contact with said push cap plate and a spring held under stress by said terminal member and acting against said plunger.

the end opposite to said terminal member, a push cap carrying a metal plate having a threaded hole to engage the threaded end of the thimble, said plate overlapping said casing and adapted to contact therewith, a spring carried by said thimble and having one end engaging said terminal member to normally keep the plate carried by the push cap out of contact with the end of said casing, said thimble being so proportioned and fitted in the insulator that the push cap cannot tilt when operated to close a circuit, and further means for assisting in keeping the push button plate away from the end of the casing and in completing said circuit consisting of; a plunger carried by the insulator and having one end projecting into contact with said push cap plate and a spring held under stress by said terminal member and acting against said plunger, and a conductor independent of said spring for permanently connecting said terminal member and plunger. 70 75 80 85

10. In a device of the class described, a
casing having an inturned flange and an in-
sulator positioned within the casing against
the flange and extending to a point near the
other end of the casing with a wire terminal
member fitting into the insulator at this end,
an insulator fitting over the said terminal
member and held in place by punching over
the rim of the casing or part thereof, means
for completing a circuit from the terminal
member to the casing including; a thimble
carried by the insulator and having an end
projecting beyond the insulator at the end
opposite to said terminal member, a push cap
carrying a metal plate with means for en-
gaging the projecting end of the thimble,
said plate overlapping said casing and
adapted to contact therewith, a spring car-
ried by said thimble and having one end en-
gaging said terminal member to normally
keep the plate carried by the push cap out of
contact with the end of said casing, and fur-
ther means for assisting in keeping the push
button plate away from the end of the cas-
ing and in completing said circuit consisting
of; a plunger carried by the insulator and
having one end projecting into contact with
said push cap plate and a spring held under
stress by said terminal member and acting
against said plunger.

11. In a device of the class described, a casing having an inturned flange and an insulator positioned with the casing against the flange and extending to a point near the other end of the casing with a terminal member fitting into the insulator at the end with means for preventing said terminal member from rotatably shifting and means including an insulator and a part of the rim of the casing for holding the said terminal member from shifting laterally, means for completing a circuit from said terminal member to 120 125 130

the casing including; a thimble carried by the insulator and having an end projecting beyond the insulator at the end opposite to said terminal member, a push cap carrying a metal plate with means for engaging the projecting end of the thimble, said plate overlapping said casing and adapted to contact therewith, a spring carried by said thimble and having one end engaging said terminal member to normally keep the plate carried by the push cap out of contact with the end of said casing, and further means for assisting in keeping the push button plate away from the end of the casing and in completing said circuit consisting of; a plunger carried by the insulator and having one end projecting into contact with said push cap plate and a spring held under stress by said terminal member and acting against said plunger. 15

In testimony whereof, I affix my signature. 20
EDWARD B. NOWOSIELSKI.
